Primary Examiner—Carol Rademaker

(57) **CLAIM**

The ornamental design for packaging for a bag dispenser, as shown and described.

DESCRIPTION

FIG. 1 is a front, top and side perspective view of packaging for a bag dispenser embodying my new design, illustrated in place over exterior surfaces of an exemplary bag dispenser shown in phantom;

FIG. 2 is a front, top and side perspective view of the packaging for a bag dispenser illustrated in FIG. 1;

FIG. 3 is a front elevational view thereof;

FIG. 4 is a rear elevational view thereof;

FIG. 5 is a left side elevational view thereof;

FIG. 6 is a right-side elevational view thereof;

FIG. 7 is a top plan view thereof; and,

FIG. 8 is a bottom plan view thereof.

The broken lines shown in the drawings are for illustrative purposes only and form no part of the claimed design.
